UNITED STATES PATENT OFFICE.

ELWIN H. KIDDER, OF CHICAGO, ILLINOIS, ASSIGNOR TO LINK-BELT COMPANY, OF CHICAGO, ILLINOIS, A CORPORATION OF ILLINOIS.

CLAMPING DEVICE FOR CAR UNLOADERS.

Application filed March 19, 1925, Serial No. 16,617. Renewed September 24, 1926.

My invention relates to improvements in clamping device for car unloaders and embodies a clamping device which will operate automatically to clamp a car on the unloading frame when the frame or cradle rotates to dump the car. One object of my invention is to provide such a device as will be easily and conveniently operated, will be automatic in its operation and will always exert a sufficient amount of power to insure proper functioning of the apparatus. Other objects of my invention will appear from time to time in the specification and claims.

My invention is illustrated more or less diagrammatically in the accompanying drawings, wherein—

Figure 1 is a side elevation of the unloader;

Figure 2 is a section along the line 2—2 of Figure 1 showing the clamp mechanism in elevation; and

Figure 3 is a view similar to Figure 2 showing the unloader in partly rotating position with the clamp in operation.

Like parts are indicated by like characters throughout the specification and drawings.

A is a cradle mounted on a plurality of ring frames A¹, which frames travel on rollers A² adapted to be rotated to rotate the ring frame and cradle by means of power applied through a drive shaft A³. A⁴ is a transfer table supported on rollers A⁵, A⁶ by means of inclined wedge blocks A⁶, A⁶ on the cradle. A⁷ A⁷ are car tracks on the transfer table adapted to support a car A⁸.

There may be two or more of the ring frames, depending on the length of the cradle and the length of the cars to be dumped thereby. Associated with each of these ring frames is an automatic clamping device which forms the subject matter of the present invention. This automatic clamping device is adapted to come down and grip the top of the car body and hold it on the tracks so that when the cradle is rotated and the car is turned upside down with the dumping, the car will be held in place without leaving the rails. The clamping arrangement is the same for each ring frame and a description of one, of course, suffices for all.

B B¹ are guide tracks. Slidable on the

track B is a short jaw clamp B² and slidable on the track B¹ is a long jaw clamp B³. Associated with the bracket for one of the rollers A² is a stop bracket B⁴ adapted to be engaged by a lifting carriage B⁴⁰ floating on the ring frame. B⁵ is a lifting rope extending from the lifting carriage B⁴⁰ over sheaves B⁶ B⁷ at the bottom of the ring frame and B⁸ B⁹ at the top and terminating in an equalizer carriage B¹⁰. Extending from the lever B¹¹ on the equalizer carriage is the long clamp lifting rope B¹² which passes over a sheave B¹³ and a sheave B¹⁴ and is anchored on the long jaw clamp B³. B¹⁵ is a short jaw clamp lifting rope extending from the end of the lever B¹¹ over a sleeve B¹⁶ to the short jaw clamp B². Thus when the cradle is in the upright position, the lifting carriage will have engaged the stop bracket and will have been held against further movement so as to draw out the lifting rope and lift both the long and short jaw clamp. When the cradle is rotated in a counter clockwise direction, the lifting carriage B⁴⁰ will travel on its rollers B¹⁷ along the track B¹⁸ toward the sheave B⁶ and permit the clamps to descend under the force of gravity until they engage or rest upon the top of the car, the parts being so positioned that this descent of the clamps and their engagement with the car will have been completed before the cradle rotates far enough to unseat the car from the track rails on which it stands.

C is the clamp holding rope. It is anchored at one end through a relieving spring C¹, and to the short jaw clamp B². It passes over the sheaves C² and C³ to a sheave C⁴ on an equalizer sheave carriage C⁵, thence over a sheave C⁶ to an equalizer spring C⁷ anchored on the long jaw clamp B³. The equalizer carriage C⁵ is slidable along the tracks C²⁶ and a rope C²⁷ leads from this carriage over a sheave C⁸ and is wound about a drum C⁹. C¹⁰ is a lowering counterweight adapted to travel in the counterweight housing C¹¹. It is suspended by a counterweight rope C¹², which passes over a sheave C¹³ and is wound about the drum C⁹. C¹⁴ is a brake band wound about a brake drum C³⁰, on the same shaft as the drum C⁹, and adapted to be gripped upon

the brake drum by means of the lever D which is pivoted as by means of the shaft D¹.

One end of the brake band is secured as at D² to the short arm of the lever and the other is secured as at D³ to the opposite arm of the lever. Secured to the outer end of the lever is a pin D⁴ the inner end of which is formed with a plug D⁵ adapted to move longitudinally within the cylindrical spring 10 casing D⁶ which is pivoted to the frame as at D⁷. D⁸ is a spiral spring coiled within said casing and compressed between the plug D⁵ and the lower end D⁹ of the spring casing. D¹⁰ is a secondary lever also in rigid 15 relation with the shaft D¹. Pivoted to its outer end is the elongated link or rod D¹¹, the opposite end of which is pivoted as at D¹² to one arm of the bell crank lever D¹³. The opposite end of the bell crank lever carries 20 a roller D¹⁴ which normally engages a cam track D¹⁵ mounted on any suitable frame members D¹⁶ which are secured to the foundations as at D¹⁷. The upper end of the cam track is curved or inclined outwardly as at D¹⁸.

The purpose of this counterweight and drum is to draw the holding rope tight when the rotation of the cradle permits the clamps to descend. The arrangement is such 25 that as the cradle rotates after the clamps have been drawn down against the top of the car, and as soon as the roller D¹⁴ rides over the end of the cam track D¹⁵, the spring D⁸ is released and moves the lever D in clockwise direction, as shown in Figure 2 and thereby creates a tension in the brake band and holds the drum against rotation. The clamps B² B³ are thus held in holding 30 position against the weight of the car when it turns over. The relieving springs C¹ and C² permit a sufficient amount of play and resiliency to insure smooth operation and protect the apparatus from shock.

It will be evident that while I have shown 45 in my drawings an operative device, still many changes might be made in the size, shape and disposition of parts without departing materially from the spirit of my invention and I wish, therefore, that my showing be taken as in a sense diagrammatic.

The use and operation of my invention are as follows:

A gondola car to be dumped is run onto 50 the tracks on the transfer table while the cradle and associated parts are in the upright position. The cradle is then rotated in a counter clockwise direction and the car and transfer table will move to the left 55 through a limited excursion with respect to the cradle when it comes to rest against the side thereof. This rotation will continue with the lifting carriage remaining at rest 60 with respect to the stop but moving in the cradle until the clamps have travelled down

to engage the car as the sheave at the bottom of the ring frame approaches the stop carriage. This downward movement of the clamps will be assisted by the pull on the counterweight which winds up the holding rope on the drum so that this rope is taut at all times. As soon as the clamps 70 settle down on the top of the car, they can move no further and the cradle will continue to rotate, and the holding rope will 75 be held tight. Upon further rotation the roller D¹⁴ rides beyond the end of the cam track D¹⁵ and the spring D⁸ rotates the brake lever D in clockwise direction about its pivot and exerts a tension on the brake 80 band C¹⁴. This tension will be exerted before the cradle has turned far enough to cause the weight of the car to be lifted from the rails. As the rotation continues the car will gradually turn over until practically 85 its entire weight is carried by the clamps, the brake band holding the drum against rotation. The parts remain in this position until the car has gone around far enough to be dumped. 90

The car after being dumped will be returned by a return rotation of the cradle. As it rotates back, and when the roller D¹⁴ engages the inclined portion D¹⁸ of the cam track D¹⁵ the bell crank lever D¹³ will 95 be rotated, exerting a downward pull on the rod D¹¹, and through the lever D¹⁰, depressing the lever D in opposition to the spring D⁸. The tension on the brake band 100 D¹⁴ is thereby relieved. Then the lifting carriage will engage its stop and a tension will be exerted on the clamp lifting ropes and the clamps will finally be raised to the top of the cradle, drawing in on the brake 105 drum and raising the counterweight and freeing the car. The car can then be removed from the transfer table and the cradle is ready for the next dumping operation.

I claim:

1. In a rotary car dumper, a rotary car supporting cradle, a clamp adapted to hold a car thereon, and clamp holding means comprising a drum, a cable leading from the clamp and wound about the drum, and a brake adapted to lock the drum, a brake actuating lever pivoted on the cradle, spring means adapted normally to move said lever into brake actuating position, and means for resisting said movement when the cradle is in car receiving position. 115

2. In a rotary car dumper, a rotary car supporting cradle, a clamp adapted to hold a car thereon, and clamp holding means comprising a drum, a cable leading from the clamp and wound about the drum, and a brake adapted to lock the drum, a brake actuating lever pivoted on the cradle, spring 120 means adapted normally to move said lever into brake actuating position, and means 125

110

130

- for resisting said movement when the cradle is in car receiving position, comprising a cam member associated with said lever and an opposed cam member mounted adjacent 5 said cradle.
3. In a rotary car dumper, a rotary car supporting cradle, a clamp adapted to hold a car thereon, and clamp supporting means comprising a drum, a cable leading from the clamp and wound about the drum, a brake adapted to lock the drum, a brake controlling mechanism adapted normally to hold said brake in operative position, and means adapted to resist the action of said 10 mechanism when the cradle is in or near car receiving position.
4. In a rotary car dumper, a rotary car supporting cradle, a clamp adapted to hold a car thereon, clamp holding means comprising a drum, a cable leading from the clamp and wound about the drum, a brake band adapted to surround said drum, a lever to which said band is secured, yielding means adapted normally to rotate said lever 20 into tension exerting position, and means for resisting said movement of the lever when the cradle is in or near car receiving position.
5. In a rotary car dumper, a rotary car supporting cradle, a clamp adapted to hold a car thereon, clamp holding means comprising a drum, a cable leading from the clamp and wound about the drum, a brake band adapted to surround said drum, a lever to 25 which said band is secured, yielding means adapted normally to rotate said lever into tension exerting position, and means for resisting said movement of the lever when the cradle is in or near car receiving position.
6. In a rotary car dumper, a rotary car supporting cradle, a clamp adapted to hold a car thereon, clamp holding means comprising a drum, a cable leading from the clamp and wound about the drum, a brake band adapted to surround said drum, a lever to which said band is secured, yielding 30 means adapted normally to rotate said lever into tension exerting position, and means for resisting said movement of the lever when the cradle is in or near car receiving position, comprising a cam member associated with said lever and an opposed cam member positioned adjacent the cradle.
7. In a rotary car dumper, a rotary car supporting cradle, a clamp adapted to hold a car thereon, clamp holding means comprising a drum, a cable leading from the clamp and wound about the drum, a brake band adapted to surround said drum, a lever to which said band is secured, yielding 35 means adapted normally to rotate said lever into tension exerting position, and means for resisting said movement of the lever when the cradle is in or near car receiving position, comprising a bell crank lever mounted on the cradle, a connection between one arm of said bell crank lever, and the brake band lever, and a cam member mounted adjacent the cradle and adapted to engage the opposite arm of said bell crank lever.
8. In a rotary car dumper, a rotary car supporting cradle, a clamp adapted to hold a car thereon, clamp holding means comprising a drum, a cable leading from the clamp and wound about the drum, a brake band adapted to surround said drum, a lever to which said band is secured, a cylindrical 40 guide pivoted adjacent said spring, a stem axially movable along said guide, a connection between said stem and the brake lever, and yielding means adapted normally to move said stem along said guide, to rotate said lever into braking position.
9. In a rotary car dumper, a rotary car supporting cradle, a clamp adapted to hold a car thereon, clamp holding means comprising a drum, a cable leading from the clamp and wound about the drum, a brake band adapted to surround said drum, a lever to which said band is secured, a cylindrical 45 guide pivoted adjacent said spring, a stem axially movable along said guide, a connection between said stem and the brake lever, and yielding means adapted normally to move said stem along said guide, to rotate said lever into braking position, and means for resisting said movement of the lever when the cradle is in or near car receiving position.
10. In a rotary car dumper, a rotary car supporting cradle, a clamp adapted to hold a car thereon, clamp holding means comprising a drum, a cable leading from the clamp and wound about the drum, a brake band adapted to surround said drum, a lever to which said band is secured, a cylindrical 50 guide pivoted adjacent said spring, a stem axially movable along said guide, a connection between said stem and the brake lever, and yielding means adapted normally to move said stem along said guide, to rotate said lever into braking position, and means for resisting said movement of the lever when the cradle is in or near car receiving position.
11. In a rotary car dumper, a rotary car supporting cradle, a clamp adapted to hold a car thereon and clamp holding means comprising a drum, a cable leading from the 55

clamp and wound about the drum, a counterweight cable wound about the drum, a counterweight carried thereby and adapted to rotate the drum to keep the clamp cable tight, a brake adapted to lock the drum, a brake actuating lever pivoted on the cradle, spring means adapted normally to move said

lever into brake actuating position, and means for resisting said spring means when the cradle is in car receiving position.

Signed at Chicago, county of Cook and State of Illinois, this 10th day of March, 1925.

ELWIN H. KIDDER.
